Inventor.

H. M. Myers.

United States Patent Office.

HENRY M. MYERS, OF ALLEGHENY CITY, PENNSYLVANIA.

Letters Patent No. 64,691, dated May 14, 1867.

IMPROVEMENT IN THE MANUFACTURE OF SHOVELS.

The Schedule referred to in these Letters Patent and making part of the same.

TO ALL WHOM IT MAY CONCERN:

Be it known that I, HENRY M. MYERS, of the city and county of Allegheny, and State of Pennsylvania, have invented a new and useful Improvement in the Manufacture of Shovels; and I do hereby declare that the following is a full and exact description thereof, reference being had to the accompanying drawing, and to the letters of reference marked thereon.

My invention consists in casting steel blanks for forming shovel-blades, as hereinafter described.

To enable others skilled in the art to make and use my invention, I will proceed to describe its construction and operation. In the accompanying drawing—

Figure 1 is a perspective view of one of my improved cast blanks for shovel-blades.

Figure 2 represents a longitudinal section of the same.

In the drawings, A represents the part of the blank from which the shovel-blade is formed; B and C represent the tangs, which form the handle-straps; D represents the socket for the end of the handle. I construct the blanks of the form represented in drawings, by casting melted steel in suitable metallic moulds. I then forge and form the shovel-blade and straps for the handle in the usual manner.

Having thus described the nature, construction, and operation of my improvement, what I claim as of my invention, is—

A blank for a shovel-blade and handle-straps, when said blank is cast of steel, substantially as herein described and for the purpose set forth.

H. M. MYERS.
